(57) **CLAIM**

The ornamental design for an in-vehicle cluster, as shown and described.

DESCRIPTION

FIG. 1 is a top front perspective view of an in-vehicle cluster showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof showing that the present cluster is installed inside a vehicle;

FIG. 9 is a perspective view thereof showing the present cluster with its rear cover open;

FIG. 10 is a front elevational view thereof showing the present cluster with its rear cover open;

FIG. 11 is a rear elevational view thereof showing the present cluster with its rear cover open;

FIG. 12 is a left side elevational view thereof showing the present cluster with its rear cover open;

FIG. 13 is a right side elevational view thereof showing the present cluster with its rear cover open;

FIG. 14 is a top plan view thereof showing the present cluster with its rear cover open; and,

FIG. 15 is a bottom plan view thereof showing the present cluster with its rear cover open.

The broken lines depict environmental subject matter only and form no part of the claimed design.
